(57) **CLAIM**

We claim the ornamental design for a portable nebulizer, as shown and described.

DESCRIPTION

FIG. 1 is a front perspective view of a portable nebulizer showing our new design;

FIG. 2 is a back perspective view thereof;

FIG. 3 is a top plan view thereof;

FIG. 4 is a bottom plan view thereof;

FIG. 5 is a right-side elevation view thereof, the left-side being a mirror image;

FIG. 6 is a front elevation view thereof; and,

FIG. 7 is a back elevation thereof, showing the portable nebulizer.

The broken lines shown in the drawings illustrate portions of the article and form no part of the claimed design.

1 Claim, 7 Drawing Sheets
